CLAIM

The ornamental design for an adapter for transfer of medical solution, as shown and described.

DESCRIPTION

FIG. 1 is a perspective view of an adapter for transfer of medical solution showing our new design;
FIG. 2 is a front view thereof, the opposite side being a mirror image of the side shown herein;
FIG. 3 is a right side view thereof, the opposite side being a mirror image of the side shown herein;
FIG. 4 is a top view thereof; and,
FIG. 5 is a bottom view thereof.
